CLOCK RADIO

Jean O. Reinecke, Oak Park, Ill., assignor to Zenith
Radio Corporation, a corporation of Delaware

Application November 10, 1958, Serial No. 53,337

Term of patent 7 years

(Cl. D56—4)

FIG. 1

FIG. 2

FIG. 3

FIG. 4

Figure 1 is a perspective view of a clock radio showing my new design;

Figure 2 is a side elevational view thereof;

Figure 3 is an enlarged front elevational view thereof; and

Figure 4 is a fragmentary sectional view taken on the line 4—4 of Figure 3.

The back of the cabinet is plain. The dominant features of my design reside in those portions shown by means of full lines in the drawing.

I claim:

The ornamental design for a clock radio, substantially as shown and described.
